UNITED STATES PATENT OFFICE.

GASTON NAVARRE, OF BOULOGNE-SUR-SEINE, FRANCE.

TYPEWRITING MACHINE.

Application filed March 30, 1921. Serial No. 456,977.

(GRANTED UNDER THE PROVISIONS OF THE ACT OF MARCH 3, 1921, 41 STAT. L., 1313.)

To all whom it may concern:

Be it known that I, GASTON NAVARRE, a citizen of the French Republic, and a resident of 23 rue Vauthier, Boulogne-sur-Seine, France, have invented new and useful Improvements Relating to Typewriting Machines (for which I have filed an application in France Mar. 29, 1919, Patent Number 509,609, Aug. 21, 1920), of which the following is a specification.

My invention relates to type-writing machines and more particularly to an alarm device for indicating the end of the page, of the kind in which an acoustic signal, actuated through the displacement of the line spacing lever, gives warning that a predetermined number of lines has been written.

My improved device is adapted to be mounted on any existing type-writing machine and has the advantage of great simplicity; moreover it comprises means permitting an easy control of the number of lines desired to be written on each page.

The annexed drawing represents, by way of example one form of construction of the device according to the present invention, adapted to be fitted to a type-writing machine of the kind known as Underwood No. 5.

Fig. 1 is a plan view of the device. Fig. 2 is a corresponding elevation thereof. Figs. 3, 4 and 5 are detail views.

The alarm device for indicating the end of the page on typewriting machines comprises essentially a frame *a*, of shape and dimensions suited to the kind of type-writing machine upon which it is to be fitted. In the example described, the apparatus is fixed upon the machine by means of two screws, upon the left-hand side of the carriage.

Upon the frame *a* there is placed a wheel *b* graduated and notched, threaded upon an axle *c* and movable around the axle. A spiral spring *f*, located in the centre of the wheel *b*, tends to return this wheel to its starting point. A tappet *g* fixed upon the graduated wheel *b*, abuts against the stop *g'*, thus regulating the starting point of the wheel *b*.

Upon the axle *c* there is provided a needle or pointer *d*, movable around this axle, and adapted to be turned by means of a knob *e*. This pointer *d* engages at its other extremity in any one of the notches in the graduated

wheel *b*, each notch corresponding to one of the interline spaces of the type-writing machine upon which the apparatus is mounted. This end of the needle engaged in the notch projects slightly beyond the circumference of the graduated wheel *b*, and is intended to act during the rotation of this wheel, upon the trip *k*, tilting the hammer *h* which under the pull exerted by the spring *j* strikes sharply against the gong *i* producing the alarm sound.

Upon the frame *a* there is fitted a pawl *m* sliding in a guide-way and adapted to be engaged with or disengaged from the graduated wheel *b* by means of the knob *l*.

A rod *n*, sliding in the parts *r* and *s*, comes into engagement at one end with one of the notches in the graduated wheel *b*; the other extremity of this rod is bent back so that the line-spacing lever or any moving part of the type-writing machine comes into engagement with this member, imparting to it a forward movement which produces the rotation of the graduated wheel *b*. A spring *e*, fixed at one end to the rod *n* and at the other end to the frame *a*, tends to return this rod to its initial position.

The apparatus when fixed upon the type-writing machine operates in the following manner:

After the paper has been engaged and gripped upon the roller of the type-writing machine, the button *l* is operated to push the pawl *m* into engagement with one of the notches on the graduated wheel. By means of the knob *e*, the needle *d* is then turned so that its extremity engages in one of the notches of the graduated wheel corresponding to the number of lines which it is desired to typewrite. The apparatus is then ready to operate.

At each change of line, the line-spacing lever of the type-writing machine abuts against the cranked end of the sliding rod *n* thus producing movement of this rod and therefore rotation of the wheel *b* to the extent of one notch. This wheel, after revolving one notch and displacing the pawl *m* is retained in the new position by this same pawl. When the graduated wheel has thus revolved through the given number of notches,—in other words the number of lines typed, since each notch corresponds to one inter-line space—the end of the needle *d*

bears against the trip *k*, thus tilting the hammer which strikes the gong *i*, thereby warning the operator that he has reached the end of the number of lines which he had 5 proposed to write.

By means of the knob *l*, the pawl *m* is then withdrawn and the graduated wheel returns automatically to its starting position by the action of the spiral spring *f*.
10 When the tappet *g* strikes against the stop *g*¹, the graduated wheel is held, and the apparatus is ready for another operation.

It will be understood that the apparatus can be arranged in indifferent ways, can 15 be fitted in any manner upon any part of the type-writing machine; it may be integral with the frame or the carriage of the machine instead of being fitted thereto.

The above described device offers the following advantages: it is of a great simplicity of construction, and all its members 20 are within reach and within sight, which has for result a very easy adjustment according to the number of lines it is desired 25 to be written.

What I claim is:

In an adjustable alarm device for type-writing machines, of the type actuated through the line-spacing lever, the combination 30 of a frame adapted to be secured to the carriage of the type-writing machine, a graduated ratchet wheel rotatably mounted

on said frame, a rod adapted to slide on the frame, a nose provided at one end of said rod and against which the line-spacing lever 35 directly abuts at each change of line, a pawl member at the other end of said rod engaging with the ratchet wheel and adapted to directly rotate the same at each actuation of the rod by the line-spacing lever, a rotatable pointer adjustably mounted on the graduated ratchet wheel, a hammer fulcrumed upon the frame, trip means carried by the hammer and actuated by the rotatable pointer to actuate the said hammer when the said 40 pointer rotates in one direction, said trip permitting said pointer to pass by the same without actuating said hammer when said pointer rotates in the other direction, a gong against which said hammer strikes, a 45 spiral spring adapted to be wound up by the rotation imparted to the ratchet wheel by the pawl member of the sliding rod and to automatically return the said wheel to its starting position, and a hand operated 50 stop pawl carried by the frame and engaging the ratchet wheel.

In testimony whereof I have signed my name to this specification.

GASTON NAVARRE.
